Primary Examiner — Jae Liang*Assistant Examiner* — Christopher Torma(74) Attorney, Agent, or Firm — Mitchell Law PLLC;
Matthew W. Mitchell(57) CLAIM

The ornamental design for a corner furniture set as shown.

DESCRIPTION

FIG. 1 is a front perspective view of the corner furniture set of the present invention;

FIG. 2 is a rear perspective view thereof;

FIG. 3 is a left-side view thereof;

FIG. 4 is a right-side view thereof;

FIG. 5 is a front view thereof;

FIG. 6 is a rear view thereof; and,

FIG. 7 is a top plan view thereof.

The stippling in the drawings show shading that defines and does not reflect a particular surface ornamentation or material.

1 Claim, 7 Drawing Sheets(56)
